LIGHTER STRUCTURE FOR GAS BURNERS

Ervin H. Mueller, Grosse Pointe, Mich.

Application August 11, 1939, Serial No. 289,539

4 Claims. (Cl. 158—115)

This invention relates to a lighter structure for gas burners and it has to do particularly with an arrangement which involves the mounting of flash tubes of an automatic lighter.

It is, of course, an old expedient to place a burner for a pilot flame, which is designed to burn substantially constantly, in some intermediate position as regards the plurality of gas burners and to extend a so-called flash tube from a point in proximity to the pilot flame to each burner for igniting purposes. When the valve for a particular burner is opened the gas flows through the flash tube and is ignited by the pilot flame, and there is a flash back through the tube to ignite the burner.

The present invention is directed particularly to the mounting of the flash tubes at or adjacent the pilot flame. One of the objects is to have an arrangement which is simple in structure and can be cheaply manufactured, and at the same time the tubes have somewhat of a universal mounting, to the end that the burners may be placed wherever desired and the flash tubes disposed in any direction from the pilot flame to the burners. Some manufacturers prefer to dispose their burners in accordance with their own ideas, and the disposition of the burners may be different in different gas ranges, but this one lighter structure may be used with any such arrangement. Moreover, the flash tubes extend outwardly radially from the pilot flame and may be disposed to extend in most any direction, and even though the position of a flash tube be changed or varied in any manner, it remains substantially on a true radial line from the pilot flame, with the result that the open end of the flash tube substantially directly faces the pilot flame.

A structure for carrying out the invention is disclosed herein.

Fig. 1 is a general plan view illustrating an arrangement of a plurality of burners with the lighter structure associated therewith.

Fig. 2 is an enlarged plan view of a pilot flame housing and the inner ends of the flash tubes, illustrating in dotted lines how a flash tube may be adjusted about the flame.

Fig. 3 is a cross sectional view taken substantially on line 3—3 of Fig. 2.

Fig. 4 is a detail view showing the formation of the flash tubes.

Fig. 5 is a detail view illustrating the formation of the pilot flame housing.

The arrangement shown in Fig. 1 is designed to depict a plurality of gas burners such as might be employed in a gas range, the stove housing being illustrated at 1, the gas supply pipe at 2, and a plurality of burners 3, each having a valve 4 for the control of gas from the conduit 2. To facilitate the illustration of the invention an auxiliary burner 5 is shown to which gas may be sup-

plied also through a valve 4. A gas pipe 6 extends from the conduit 2 for the purpose of supplying gas to the pilot flame.

Each burner is constructed to receive one end 5 of a flash tube 7 arranged in the usual manner to supply gas to the tube when gas is supplied from the corresponding valve 4. As illustrated, the flash tubes comprise two telescoping tubes so that the length thereof may be varied.

The pipe 6 connects to an upwardly extending mixer tube 10 (Fig. 3) disposed in a more or less central position, and the pilot flame housing is carried by the mixer tube. This housing, as illustrated in Figs. 3 and 5, preferably takes the 15 form of a sheet metal stamping of cup shape, having the central portion of its bottom secured to the mixer tube 10 as at 11 and having a plurality of secondary air apertures 12. The housing has a circular wall which extends preferably substantially vertically as illustrated at 13 and the upper edge has a bead formation 14 advantageously formed by fashioning the metal back upon itself as shown. This bead formation is continuous except where it is cut away as at 15 to provide 20 a notch. This notch is preferably located over or in substantial alignment with the pipe 6. Of course, more than one notch 15 may be provided but it is preferred that only one be used. The mixer tube 10 is preferably equipped with a pilot 25 flame tip 16 for the pilot flame, which itself is illustrated at 17. It is sufficient that the housing be a support for the flash tubes, it not being necessary that the housing actually perform a 30 housing function for the flame.

The ends of the flash tubes adjacent the pilot flame are arranged to be connected to the housing or cup, and more particularly with the bead 14. To this end each flash tube has a cut-out 35 portion to form an aperture which, as illustrated, is somewhat in the shape of a figure eight; the aperture has enlarged ends 20 and 21 with a constricted central portion 22.

To mount a flash tube on the cup, the tube is placed so that it lines up with the notch 15; in other words, as in Fig. 1 is viewed the flash tube is placed in substantial alignment with the pipe 6, and then is lowered into the notch 15. The defining portions of the constricted part 22 pass down into the notch. Then the tube may be 45 swung circumferentially with the bead then engaging in the two end portions 20 and 21. The constricted portions at this time underlie the bead as shown in Fig. 3 so that the tube is firmly held attached to the cup.

It will be observed that any number of flash tubes may be placed on the cup, the number being limited by the capacity of the circumferential rim and that the flash tubes may be disposed at any desired radial position. Therefore, the burners may be disposed wherever desired and the flash tubes adjusted to extend 50 60

radially from the pilot flame to the burner. To illustrate this a little more definitely there is shown an auxiliary burner 5, which is one more than the usual number of burners, and it will be seen how it is merely necessary to place an additional flash tube for the burner. In other words, the arrangement of the housing is not specifically constructed so that it is limited to use with any definite number of flash tubes.

There is another feature in this connection which is important. The arrangement is such that the pilot flame is substantially centrally disposed relative to the rim of the cup. It follows that when a flash tube is angularly adjusted it swings around the pilot flame as a center, as distinguished from an arrangement where the flash tube has a connection with the housing such that the flash tube would pivot on the housing. As a result, all the flash tubes extend substantially on a true radial line from the pilot flame as a center and therefore the flash tubes open directly toward the pilot flame. This is illustrated by the full and dotted line positions of Fig. 2 showing the adjustment of one of the flash tubes. Where a flash tube pivots on a housing the inner end is caused to swing away from the pilot flame if there be any adjustment.

The arrangement of the bead 14 and the apertures in the flash tubes are such that the bead slides nicely in the enlarged portions 20 and 21, while the restricted portions underlie the bead but do not bind on the bead or the wall of the cup. This facilitates assembly and also permits a slight pivotal action of the flash tubes relative to the housing on a horizontal axis. This takes care of any difference in the elevation of any one of the burners relative to the housing. Inasmuch as the flash tubes are not permanently united with the housing, the structure may be shipped in disassembled relation, and it is very easy to slip the tubes into position. The notch 15 is preferably located adjacent the pipe 6 for the reason that there is usually no burner in a position which requires a flash tube to parallel the pipe 6.

I claim:

1. In a lighter structure for a plurality of gas burners grouped around a pilot flame, a supporting cup member having an upstanding circumferential wall, said wall having a bead formation on its upper edge, the upper edge of the wall having at least one notch formation therein which cuts through the bead, and said wall and bead being otherwise uninterrupted throughout, means for supplying gas to the central portion of the cup for the pilot flame, flash tubes for extending from the pilot flame to the burners, each flash tube having a slot in its wall adjacent the pilot flame end thereof, said slot being elongated circumferentially of the tube and having enlarged end portions and a constricted intermediate portion, the constricted intermediate portion having a cross dimension less than that of the bead and adapted to pass into the notch formation, whereby upon shift of the tube along the wall the parts defining the constricted portion engage under the bead, the enlarged end portions of the slot freely receiving the bead so that the tube, when thus engaged therewith, is slideable throughout the extent of the wall.

2. In a lighter structure for a plurality of gas burners grouped around a pilot flame, a supporting member comprising an upstanding cir-

cumferential wall, said wall having a bead formation on its upper edge, the upper edge of the wall having at least one notch formation therein which cuts through the bead, and said wall and bead being otherwise uninterrupted throughout, means for supplying gas substantially centrally within the wall for the pilot flame, flash tubes for extending from the pilot flame to the burners, each flash tube having a slot in its wall adjacent the pilot flame end thereof, said slot being elongated circumferentially of the tube and having enlarged end portions and a constricted intermediate portion, the constricted intermediate portion having a cross dimension less than that of the bead and adapted to pass into the notch formation, whereby upon shift of the tube along the wall the parts defining the constricted intermediate portion engage under the bead to hold the tube on to the wall, the enlarged end portions of the slot freely receiving the bead so that the tube, when thus engaged therewith, is slideable throughout the extent of the wall.

3. In a lighter structure for a plurality of gas burners grouped around a pilot flame, a supporting member comprising an upstanding circumferential wall, said wall having a formation on its upper edge with a radial dimension greater than the thickness of the wall whereby to overhang the wall, the upper edge of the wall having at least one notch formation therein which cuts through the said formation and said wall and formation being otherwise uninterrupted throughout their circumferential extent, means for supplying gas substantially centrally within the circumferential wall for the pilot flame, flash tubes for extending from the pilot flame to the burners, each flash tube having a slot in its wall adjacent the pilot flame end, said slot being elongated circumferentially of the tube and having enlarged end portions and a constricted intermediate portion, the constricted intermediate portion having a cross dimension less than the radial dimension of the formation on the upper end of the wall and adapted to pass into the notch formation, whereby upon shift of the tube along the wall the parts defining the constricted intermediate portion engage under the formation on the upper edge of the wall to hold the tube on to the wall, the enlarged end portions of the slot freely receiving said formation so that the tube, when thus engaged therewith, is slideable throughout the extent of the wall.

55 4. In a lighter structure for a plurality of gas burners grouped around a pilot flame, a supporting cup member having an upstanding circumferential wall, the upper edge of the wall being fashioned to provide an integral formation having a radial dimension greater than the thickness of the wall whereby to overhang the same, means for supplying gas to the central portion of the cup for the pilot flame, flash tubes for extending from the pilot flame to the burners, the end of each flash tube adjacent the pilot flame having a notch formation extending through its wall for engaging the overhanging formation on said wall including a part for engaging underneath the overhanging formation and a recess formation for freely receiving said overhanging formation so that each tube, when thus engaged with said formation, is slideable throughout the circumferential extent of said wall.
